CLAIM

We claim the ornamental design for a label base with indicator tab for industrial bins, as shown and described.

DESCRIPTION

FIG. 1 is a top front left perspective view of a label base with an indicator tab for use with an industrial bin.

FIG. 2 is a bottom front left perspective view thereof.

FIG. 3 is a rear plan view thereof.

FIG. 4 is a front plan view thereof.

FIG. 5 is a left side plan view thereof.

FIG. 6 is a bottom plan view thereof.

FIG. 7 is a top plan view thereof.

FIG. 8 is a front right perspective view thereof, with indicator tab extended; and,

FIG. 9 is a front plan view thereof with indicator tab extended.
